US0D1028282S

(12) **United States Design Patent** (10) **Patent No.:** **US D1,028,282 S**
(45) **Date of Patent:** **** May 21, 2024**

(54) **CONTAINER ASSEMBLY**

(71) Applicant: **Roche Diabetes Care, Inc.**,
Indianapolis, IN (US)

(72) Inventors: **Ernest Graeme Harvey**, Avon, IN
(US); **Michel Cadio**, Indianapolis, IN
(US)

(73) Assignee: **Roche Diabetes Care, Inc.**,
Indianapolis, IN (US)

(**) Term: **15 Years**

(21) Appl. No.: **29/888,963**

(22) Filed: **Apr. 6, 2023**

Related U.S. Application Data

(63) Continuation of application No. 29/733,630, filed on
May 5, 2020, now Pat. No. Des. 986,436.

(57) **CLAIM**

The ornamental design for a container assembly, as shown and described.

DESCRIPTION

FIG. 1 is a top perspective view of a container assembly showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the container assembly that form no part of the claimed design.

1 Claim, 7 Drawing Sheets
